LOCK CONSTRUCTION

Duncan Shaw, Haworth, N. J., Charles Sherwood, Old Greenwich, Conn., and Daniel T. Cahill, Huntington Station, N. Y., assignors to Duncan Shaw Corporation, New York, N. Y., a corporation of New York

Application May 13, 1947, Serial No. 747,668

22 Claims. (Cl. 70—146)

1

This invention relates to locking devices and more particularly to a lock for a door or the like.

The operating mechanism of most conventional door locks customarily includes various types of lever or cam and follower systems to connect the door knob and the door bolt so that the bolt may be retracted when the knob is turned in either direction. Such door knobs also frequently include a key-operated mechanism comprising a key-operable rotatable cylinder which when rotated in one direction locks the door knob or the bolt, or in some cases both. Here again lever or cam systems are usually employed to provide the operating connection between the key cylinder and the door bolt or knob.

Such lever or cam and follower systems frequently include a number of small and accordingly relatively fragile parts that are not only difficult to manufacture inexpensively, but also complicate assembly and repair procedures. Thus, for example, in several well-known door locks a rather complicated lever and cam system is utilized. This system comprises a number of operating elements which are first rough cast and then delivered in that condition to an assembler, a skilled handcraftman, who must hand-file the individual pieces until he can fit them together as an operating assembly. This, of course, inevitably leads to extremely high production costs, and comprises a production bottleneck.

Another well-known type of door lock includes a pair of buttons usually located beneath the spring bolt, one of the buttons being depressible to lock one of the knobs against keyless operation, the other button being provided to release the knob lock and restore the first button to unlocked position. One objectionable feature of this type of lock lies in the fact that only one of the knobs (almost always the outer one) is locked against rotation so that the inner one remains readily rotatable. Thus a person using the door as an exit has no way of knowing the condition of the lock without locking at the buttons, or testing the outer knob, and it frequently occurs, particularly when the individual is in a hurry, that he inadvertently locks himself out—quite a nuisance when he has forgotten his key. Another objection to this type, as well as to the other types of locks, is that they are not universal, i. e. they are either right-hand or left-hand sets, and must therefore be installed accordingly. Hence, a dealer has to stock both kinds to satisfy builders' requirements.

When it is borne in mind that modern building requirements, in many instances, specify doors that are of the order of one and three-eighths

2

inch thick, it will be realized that the mortising of such a door a sufficient amount to receive a conventional lockset mechanism leaves but little wood on opposite sides of the mortise, due to the thickness of such mechanism and the necessity of embedding it within the door. This, of course, greatly weakens the door and occasionally results in irreparable damage thereto where the installation is done in an unskilled or careless manner.

10 Indeed, one of the reasons for the excessive thickness of office, apartment and dwelling doors is the bulkiness of the lock mechanisms which must be installed therein. In this connection it might be well to note that in mortise type locksets, the pin tumbler mechanism is customarily threaded into the lock casing which is mortised into the door. This necessitates hollowing out the door in the region of the cylinder, accordingly further weakening and possibly defacing the door.

20 In many instances, it would be quite satisfactory, and indeed desirable, to use doors one inch or less in thickness. Satisfactory materials such as plywood are available and resulting economies in labor of installation as well as materials such as hinges are obvious. Door thicknesses of that order, however, may not be used where locksets are required, as the commercially available locksets are far too thick to be carried in a door of that thickness. The bulkiness of such locksets inevitably results from their characteristic structural features and operating mechanisms which can attain requisite strength and operate only through bulkiness.

30 It is accordingly among the objects of this invention to provide a lockset that is simple, inexpensive and sturdy structurally, which may be readily installed in a door, and which overcomes the aforementioned objections in addition to others in a thoroughly simple and practical manner.

40 In accordance with one form of the invention, the lockset includes conventional door knobs, connected as by a squared shaft to a rotatable drum which is attached by a flexible cable to the bolt, so that rotation of either knob in either direction 45 may retract the bolt. To lock the door knobs against operation, a latch mechanism is provided which may be controlled either by a thumb knob or by a conventional key-operated pin tumbler mechanism. The thumb knob and tumbler cylinder are operatively associated with a drum, to which the opposite ends of another flexible cable are attached, this cable, in turn, being trained around a latch operating pulley in such a manner that operation of the thumb knob, on the one 55 hand, or the tumbler cylinder on the other, ro-

tates the pulley. The pulley, in turn, is connected to a locking hub assembly which coacts with the bolt in such a manner as to preclude movement thereof by either door knob when the latch is set.

More specifically, the lockset may take the illustrative form shown in the drawing, wherein:

Figure 1 is a perspective view of a fragment of a door wherein the lockset is installed, this being an outside view thereof;

Figure 2 is a view similar to Figure 1, but showing the inside of the lockset;

Figure 3 is a substantially enlarged horizontal section of the lockset bolt mechanism and a portion of the latching mechanism therefor, taken along the line 3—3 of Figure 4;

Figure 4 is a view of the bolt and latch mechanism taken generally along the line 4—4 of Figure 3; this view, however, not being a true section, but rather being an elevation of the bolt assembly, with one cover plate thereof removed;

Figure 24 is an exploded fragmentary perspec-

4
tive view of a modified form of latching mechanism;

Figure 25 is a fragmentary perspective view of the latching mechanism of Figure 24 in locked condition;

Figure 26 is a view similar to Figure 25, but showing the latch mechanism in unlocked condition;

Figure 27 is a fragmentary sectional elevation taken along the line 27—27 of Figure 28, showing the relationship of the elements of the latch mechanism shown in Figures 24—26;

Figure 28 is a horizontal section taken along the line 28—28 of Figure 27, showing the latch mechanism in locked condition;

Figure 29 is a view similar to Figure 28, but showing the latch mechanism in unlocked condition; and,

Figure 30 is a fragmentary sectional elevation, taken along the line 30—30 of Figure 28.

Similar reference characters refer to similar parts throughout the various views of the drawings.

Referring first to Figures 1 and 2, the lockset is shown installed in a portion of a door 40, the outside of the lockset being shown in Figure 1, while Figure 2 shows the inside thereof. Thus, in general, the lockset comprises an outer knob 41, a key-operable pin tumbler cylinder 42, a bolt 43, an escutcheon plate 44 (Figure 2), an inner knob 45, and a thumb knob 46. When the lockset is unlocked, bolt 43 may be retracted by rotating either of knobs 41 or 45 in either direction. Both knobs may be locked when cylinder 42 is rotated by the proper key, or when thumb knob 46 is rotated. As will appear hereinafter, bolt 43 is retractable by operation of either knob, or upon forcibly closing the door.

40 *Bolt and bolt operating mechanism (Figures 3-14 and 20)*

As shown in Figures 3 and 4, bolt 43 is a part of an assembly which includes a housing comprising side plates 48 and 49, a front plate 50 and a scalp plate 51, the scalp and front plates adapted to be secured to the edge of door 40 as by screws 52 (Figure 1). Plates 48 and 49 (Figure 3) include guide sections 48a and 49a, which form a chamber 53 within which bolt 43 is slidably received when the bolt is retracted. The inner end of bolt 43 is secured in any suitable manner to the outer end of a tailpiece 54, which extends rearwardly from the bolt through chamber 53 between crimped portions 55 and 56 (see Figure 8) of plates 48 and 49, respectively. The inner surfaces of these crimped portions accordingly comprise a slideway for the inner end of the tailpiece. Intermediate crimped portions 55 and 56 of plates 48 and 49 are so formed as to include arcuate sections 57 and 58, which comprise a cylinder within which one end 59a of a spring 59 is received. The other end 59b of this spring (see Figure 4) encircles a lug 60 projecting into a hollowed out portion 54a of tailpiece 54. Thus the right-hand end 59a of spring 59 is seated or anchored in the lock plates under compression, to bias tailpiece 54, and accordingly bolt 43, to the left.

Referring to Figure 11, the right-hand end portion of tailpiece 54 which incidentally may be a sheet metal stamping, is bifurcated, and accordingly includes a pair of spaced fingers 61 and 62 which, as shown in Figure 10, lie in a plane that is spaced from but parallel to the left-hand end portion of the tailpiece. Integrally formed with the tailpiece are a pair of cable anchoring

lugs 63 and 64. Fingers 61 and 62 (see Figures 4 and 7) straddle a squared knob operating shaft 65 having knobs 41 and 45 (Figure 20) on its opposite ends. Also mounted on this shaft is a narrow cable drum 66 (Figures 4, 7 and 9) with annular walls 67 and 68 between which is trained a small diameter flexible steel cable 69. This cable engages 180° of the periphery of the drum and upon rotation of the door knobs, retracts bolt 43 in a manner to be described. It may illustratively be Roebling stainless steel leader cable having an outside diameter of the order of .032", made up of a plurality of individual strands of .005" diameter wire, so arranged that the cable has little elasticity, but yet great tensile strength and flexibility; this permits indefinite flexing about drum 66, without harm or breakage. This type of connector cable is preferred over a link belt or conventional stranded wire which does not stand up in use.

As is better shown in Figure 6, drum 66 is preferably an assembly of three sheet metal pieces, comprising end sections 70 and 71 and a center section 72, the end sections being flanged to provide the drum walls 67 and 68. Housing side plates 48 and 49 are annularly shouldered as at 73 and 74, respectively, to provide bearings for the outer edges of drum sections 71 and 70; this holds the drum in assembled condition when the side plates are secured together. Center section 72 includes a bifurcated lug 75 (Figure 7) through which cable 69 passes and to which it is locked as by locking rings 76 and 77, swaged or otherwise attached to the cable on opposite sides of lug 75. It may accordingly be seen that when drum 66 is rotated in either direction, cable 69 is correspondingly drawn.

With reference to Figure 4, cable ends 69a and 69b pass respectively through tailpiece anchor lugs 63 and 64, and have fastened to their ends ball-like elements 78 and 79. Interposed between ball 78 and lug 63 is a compression spring 80, a similar spring 81 being disposed between ball 79 and lug 64 on the other cable end. As shown in Figure 13, a sleeve 82 lies between ball 78 and lug 63, thus forming a positive stop which limits movement of the ball toward lug 63. Sleeve 82 is longer than spring 80 when fully compressed so that the spring may never reach full compression; continued full compression in use may seriously damage the spring over a period of use. A similar sleeve 83 (Figure 4) is located for a similar purpose between ball 79 and lug 64.

It may now be seen, with reference to Figure 12, that when shaft 65 is rotated by either door knob in a clockwise direction cable end 69a is drawn to the right so that ball 78, acting through sleeve 82 against lug 63, draws tailpiece 54 to the right against the pressure of spring 80, and accordingly retracts bolt 43 into the assembly. At the same time, end 69b of the cable is pushed to the left by the action of spring 81 expanding against ball 79, so that this cable end and spring assume the position shown when the bolt is retracted. It will, of course, be clear that rotation of shaft 65 in the opposite direction will attain the same results, except that the relative positions of the cable ends and their associated parts will be opposite to that shown.

Each of the drum walls 67 and 68 has angularly spaced shoulders to preclude rotation of drum 66 beyond desired limits in either direction of operation. Thus drum wall 68 includes shoulders 68a and 68b, (Figures 4, 12 and 13) which abut respectively against the opposite sides of a lug 84

formed on tailpiece 54. More specifically the clockwise limit of rotation of shaft 65 is determined by engagement of shoulder 68b with the lug 84, while the counterclockwise limit of rotation is determined by engagement of shoulder 68a with lug 84. By thus positively limiting rotation of the drum, the danger of jamming or otherwise damaging the bolt mechanism is precluded. Also stress on the cable, greater than that necessary to withdraw the latch bolt, is precluded.

As pointed out hereinbefore, bolt 43 may retract fully (see Figure 14) without turning either door knob, for example, when the door is forcibly closed or slammed. Under such circumstances, pressure is exerted on the outer end of bolt 43 which, of course, forces tailpiece 54 to the right, carrying with it lugs 63 and 64. As these lugs move to the right, springs 80 and 81 expand, cable 69 however, remaining stationary. Thus ends 69a and 69b extend from the lugs 63 and 64 a considerable distance but are held stiff and straight by the springs 80 and 81. Accordingly, whenever the bolt is retracted the free end or ends of the cable will be held extended and thus clear of any moving parts upon further operation.

From the above, it will now appear that the bolt and its operating mechanism are characterized by such structural simplicity as to permit manufacture of the several parts by mass production techniques. Also, the nature of the parts permits easy and rapid assembly by relatively unskilled personnel. At the same time, the bolt assembly as a unit has great structural rigidity, is easily installed in the door, and is completely devoid of complex cam and lever systems which might otherwise prevent prolonged, dependable operation. Furthermore, through utilization of the narrow drum and cable connection between door knob shaft 65 and the tailpiece 54, the bolt assembly may be kept down to minimum thickness, which permits the assembly to be embedded within a door without removing such a large amount of the door material as would weaken it. Indeed, in practice, the bolt assembly may be readily installed in a $\frac{1}{8}$ " hole in a $1\frac{3}{8}$ " door, thus leaving $\frac{1}{4}$ " of door material on each side of the mortise. Obviously thinner doors may be utilized with highly satisfactory results. Furthermore, as the casing of the bolt assembly is generally cylindrical, the mortising operation is greatly simplified.

Locking hub assembly (Figures 3-5, 15-20)

For many installations, the bolt and bolt operating mechanism heretofore described is useful alone, i. e. wherever it is unnecessary to provide a lockable door. Where, however, it is necessary or desirable to lock the door a mechanism which will hereinafter be referred to as the locking hub assembly to lock the bolt and the knob must be included, as will now be described.

As shown in Figure 3, the walls of casing sides 48 and 49 are cupped as at 85 and 86, respectively, to form bearing recesses adapted to receive the ends 87 and 88 of a hub, generally indicated at 89. The hub ends are connected by a shaft 90, which is eccentrically related to the hub ends, and which carries a pair of locking links 91 and 92. As is more clearly shown in Figure 19, link 91, which will be hereinafter referred to as the tailpiece locking link, is generally U-shaped and accordingly includes a top 93 having a downstruck lip 94 and side walls 95 and 96. These walls are respectively horizontally slotted as at 97 and 98, which slots receive the

eccentric shaft 90 of hub 89. Link 92, hereinafter referred to as the drum locking link, is also U-shaped, accordingly including an end wall 99 and projecting side walls 102 and 103, the side walls being vertically slotted respectively at 102 and 103 to receive hub shaft 90. When the two locking links 91 and 92 are assembled with hub 89, link sides 100 and 101 embrace sides 95 and 96 of the other link, while shaft 90 of the hub extends through the slots in both links, thus supporting the two links in the operative position shown in Figure 3 between side plates 48 and 49.

In Figures 15 thru 18, we have shown the elements of the locking hub assembly, namely the locking links, in their different operative relation with respect to the bolt mechanism. Thus in Figure 15, hub 89 is shown rotated clockwise from its Figure 16 position a sufficient amount to move locking links 91 and 92 into their locking positions relative to finger 61 of the bolt assembly and to drum 66 of the bolt operating mechanism. As the hub so moves, its eccentric shaft portion 90 working in the vertical slots 102 and 103 of link 92 moves this link to the left until its side wall 99 engages a flat 104 on drum 66. This interengagement between side wall 99 and drum 66 not only precludes rotation of the drum, but also prevents further movement of the link and accordingly continued rotation of the hub which would disengage the assembly. Also, during this movement of the hub, its eccentric shaft 90, working in the horizontal slots 97 and 98 of link 91, raises this link from the Figure 18 to the Figure 17 position wherein the link lip 94 is lodged against the end of tailpiece finger 61, thus precluding movement of finger 61 and accordingly the tailpiece and bolt to the right. The locking links may, of course, be moved from their latching position by reverse operation of hub 89.

These movements of hub 89 are effected by a key 105 or the like (Figure 3) which is received in a slot 106 in hub 89, and which is driven in a manner that will be hereinafter described.

In Figures 24-30, we have shown a modified form of our locking hub assembly. Thus, as shown in Figure 28, casing sides 48 and 49 journal a hub, generally indicated at 107, which has formed intermediate the ends thereof (see Figure 24) a cam plate 108 provided with lobes 109, 110 and 111 (see Figures 27 and 29). The right-hand end 107a (Figure 24) of hub 107, which is received in bearing 85 of side plate 48, extends through an opening 112 formed in a cam follower locking plate, generally indicated at 113. Plate 113 is provided with follower lobes 114 and 115, which coact respectively with cam lobes 111 and 110. Plate 113 also includes projections 116 and 117 adapted, respectively, to lie and rock in grooves 118 and 119 pressed in casing side 48 on opposite sides of bearing 85. Thus when the hub 107, plate 113 and the opposite casing sides are assembled, plate 113 is pivotable relative to side 48 about its projections 116 and 117.

Plate 113 also includes a transverse locking bar 120, at the opposite ends of which are formed locking shoulders 121 and 122 (see Figure 27). Locking bar 120 is adapted to coact with flat 104 on drum 66 (Figure 28) while shoulders 121 and 122 are adapted, respectively, to lodge against tailpiece fingers 61 and 62 (Figure 27) to lock the drum and fingers, and accordingly the bolt and its operating mechanism against operation.

This locking hub assembly is operated in a manner that will now be described. In Figure 28, the several parts of the mechanism are shown

in locked position, these parts being shown in unlocked position in Figure 29. Thus, starting from the Figure 29 position, hub 107 may be rocked clockwise, as viewed in Figure 27, by key 105, which is slidably received in a slot in the hub. As the hub so rotates, its cam 108 rotates with it and effects engagement between cam lobe 111 and follower lobe 114. This rocks locking plate 113 clockwise about its pivots 116 and 117 to the Figure 28 position, wherein bar 120 is lodged against flat 104 of drum 66, and wherein shoulders 121 and 122 (see also Figure 27) are moved to a position adjacent the free ends of tailpiece fingers 61 and 62. Thus the fingers and drum are held against movement. At the same time (see Figure 25), follower lobe 115 is moved into the path of cam lobe 109, precluding further movement of the locking plate 113 and accordingly of the cam plate 108 and hub 107; this prevents overriding of the cam and consequent unlocking of the latch.

When it is desired to unlock the locking hub assembly, hub 107 is rotated counterclockwise, as viewed in Figure 27, which movement disengages cam lobe 111 (see Figures 28 and 29) from follower lobe 114 and engages cam lobe 110 (Figure 29) with follower lobe 115, thus to rock locking plate 113 counterclockwise about its pivot to the Figure 29 position. When the locking plate 30 is in this position, its bar 120 is removed from flat 104 of drum 66, and its locking shoulders 121 and 122 are moved away from the free ends of tailpiece fingers 61 and 62, thus to permit rotation of the drum and movement of the fingers and accordingly the tailpiece and bolt. It should also be noted that this counterclockwise rocking of locking plate 113 moves its lobe 114 to the Figure 29 position, where it is interposed into the path of continued movement of cam lobe 109 (see Figures 25 and 26). Thus follower lobe 114 conveniently provides a stop which precludes excessive counterclockwise movement of hub 107, which might otherwise relock the assembly.

From the foregoing it may now be seen that either of the locking hub assemblies comprises a part of the latch bolt assembly as shown, for example, in Figures 3 and 4, and is of such a nature as to be easily included therein during the assembly operation. Furthermore, by virtue of the inclusion of the locking hub assembly in the latch bolt assembly, both the bolt and its operating mechanism and the locking hub assembly are installable as a unitary assembly when the lockset is fitted to the door. While the locking hub assembly operating mechanism, which will be described hereinafter, is adapted for a lockset including a pin tumbler type lock, it should be noted that the operating key 105, as shown in Figure 20, may be detachably connectable with an operating lever which may alternatively take the form of lever 123 (Figure 2) rotatably mounted on escutcheon plate or rose 44 for locking doors to bedrooms, bathrooms or other doors requiring no pin tumbler application. Where this type of lever is used, of course, thumb knob 46 may be dispensed with and it will therefore be understood that the lockset customarily does not include both the thumb knob and the lever.

70 Locking hub assembly operating mechanism (Figures 20-23)

Where the locking hub assembly heretofore described is to be used in conjunction with a pin tumbler or other type of key-operated lock, we

prefer to employ mechanism therefor of the type illustratively shown in Figures 20-23. Thus as shown in Figure 21, the operating mechanism includes a winding drum 124 and a pair of narrow pulleys 125 and 126, the drum and pulleys adapted to carry a flexible steel cable, similar to cable 69, trained thereabout and fastened thereto. The ends 127a and 127b are secured in any suitable manner, as within a slot 124a, to drum 124, and each of pulleys 125 and 126 carries one turn of the cable, these turns of the cable being respectively fastened to the pulleys as by clips 128 and 129. Thus it follows that as drum 124 is rotated in one direction or another, each of the pulleys is constrained to rotate accordingly.

As noted hereinbefore, it is one of the objects of our invention to provide a universally applicable lockset, i. e. one that may be applied either to a right-hand or a left-hand door. In our illustrative embodiment of the lockset, we have shown what might be termed a left-hand lockset. In this type of lockset, accordingly, pulley 125 (Figure 21) is employed to operate the locking hub assembly while pulley 126 merely idles. Thus pulley 125 has holes 130 and 131 formed therein which respectively receive the bifurcated ends 132 and 133 of key 105 (see Figure 20). It will now appear that as drum 124 is rotated in one direction or another, pulley 125 is driven accordingly to rock key 105. This movement of the key, of course, locks or unlocks the locking hub assembly, as hereinbefore described, and accordingly locks or unlocks the door knob shaft and bolt. When the lockset is to be oppositely applied, i. e. to a right-hand door pulley, pulley 126 is the operative pulley while pulley 125 idles. Thus the key 105 (Figure 20) is inserted in whichever pulley 125 or 126 is required by the brand of the door.

As shown in Figure 20, drum 124 and pulleys 125 and 126 (pulley 125 only is shown in this figure) are disposed in a space 134 provided therefor, which space is formed by front escutcheon plate 44 and a rear escutcheon plate 135, these two plates being secured together in any suitable manner as, for example, by a rivet 136. Drum 124 is preferably integrally formed with thumb knob 46, and includes a bearing portion 137 which is rotatably received in a hole 138 formed in the upper portion of the front escutcheon plate. The drum and thumb knob are rotatably retained in the position shown by a retaining washer 139 which may be of a type to snap into a reduction 140 formed between drum 124 and bearing 137.

Each of the pulleys 125 and 126 is rotatably mounted in the lower part of space 134. Thus pulley 125 includes a journal 141 adapted to be received and rotate in a hole 142 formed in rear escutcheon plate 135, the left-hand flange 143 of this pulley bearing against the outer surface of the rear escutcheon plate. The right-hand flange 144 of pulley 125 rests against the inside of front escutcheon plate 44 when the two plates are fastened together, thus to rotatably retain pulley 125 in proper operative position therebetween. Pulley 126 (Figure 21) is similarly mounted between the two escutcheon plates. Both escutcheon plates and their contained mechanism are secured to the side of door 40, as by screws 145 (Figure 2).

Door 40 (Figure 20) has a hole 146 cut therethrough, and this hole receives a key-operated locking cylinder, generally indicated at 147, of the pin tumbler type. Thus lock 147 includes a barrel 148, the rear wall 149 of which threadably

receives a retaining screw 150 which extends through and heads against a retainer plate 151 having a reentrant portion 152 which is received in hole 146, and a flange 153 which rests against the door side. Thus cylinder 147 is securely mounted in door 40. Preferably a suitably flanged cylinder collar 154 is interposed between the front side of barrel 148 and the adjacent door side, but if desired the cylinder barrel and/or its cylinder collar may be received within door 40 so that the outer surfaces of the cylinder and door are flush.

Cylinder 147 includes a pin tumbler cylinder plug 155 which, when the proper key is inserted in a keyhole 156 may be rotated relative to barrel 148, accordingly to rotate a tailpiece 157 or the like secured to the cylinder. This tailpiece extends through holes 158 and 159 formed, respectively, in retainer plate 151 and rear escutcheon plate 135, and passes through a slot 160 formed in a sector dog 161, which is provided with an instruck lug 162. This sector dog is generally cup-shaped and fits over the inner end of cable drum 124 so that its instruck lug 162 may ride in an arcuate slot 163 formed in the periphery of the drum. This slot is better shown in Figures 22 and 23.

Slot 163 is not completely annular, and accordingly includes a limit or stop shoulder 164 at one end, and a similar stop 165 at the other. Thus lug 162 may move in slot 163 relative to stops 164 and 165 when the key in cylinder 147 is turned while the reverse action takes place upon turning of thumb knob 46. It may then be seen that when the locking hub assembly operating mechanism is being operated by a key in lock 147, rotation of cylinder plug 155 rotates tailpiece 157 and accordingly sector dog 161 until its lug 162 engages either of stops 164 or 165 in drum groove 163. Continued rotation of the sector dog by the key accordingly rotates drum 124, and thereby operates the locking hub assembly operating mechanism in the manner hereinbefore described.

If, on the other hand, the locking hub assembly operating the mechanism is operated by thumb knob 46, the knob can be rotated in one direction or the other until one or the other of its stops 164 or 165 engages lug 162. Thus it follows that the locking hub assembly operating mechanism can be operated by thumb knob 46 independently of key lock 147, whereas operation of this mechanism by a key also rotates thumb knob 46, by reason of its interconnection therewith by cable drum 124.

From the foregoing it may now be seen that practically all of the operating parts of both the latch bolt and the locking hub assembly and of the operating mechanisms therefor, are simple castings of the type that need little or no machining, or are simple sheet metal stampings, the various parts being so related operatively and coacting in such a manner as to preclude the necessity of precision machining to fine tolerances. Furthermore, these several parts may be readily and rapidly assembled in accordance with mass production techniques without the necessity of nicely fitting any of them, or of resorting to machine work or handcraftsmanship to make the parts fit. It might also be well to note that it is only necessary to drill three holes in the door to accommodate the different assemblies namely, a hole for the reception of the latch bolt and locking hub assembly, a hole transverse to this one for the reception of the door knob shaft,

11

and hole 146 for the reception of the pin tumbler cylinder and its associated parts. Thus the necessity of cutting a large mortise in the door is precluded, as the interconnection between the pin tumbler cylinder and the thumb knob, on the one hand, and the locking hub assembly on the other, is effected by a few simple, compact parts which may be readily carried on the outside of the door under the escutcheon plate.

It accordingly follows that we have provided a lockset that attains the several objects set forth hereinbefore in a thoroughly practical and efficient manner.

As many possible embodiments may be made of the above invention, and as many changes may be made in the embodiments above set forth without departing from the scope thereof, it is to be understood that all matter hereinabove set forth or shown in the accompanying drawings is to be interpreted as illustrative only and not in a limiting sense.

We claim:

1. In a lockset, in combination, an elongated housing adapted to be received in a mortise or the like in a door, a bolt slidably mounted in one end of said housing and movable between extended and retracted positions, a locking hub assembly mounted in the other end of said housing and movable between locking and unlocking positions, an elongated bolt moving member disposed within said housing and secured at one end to said bolt, the other end of said member lying adjacent said assembly when said bolt is in extended position, means for moving said assembly to its locking position wherein it lies in the path of retracting movement of said member, thereby to preclude retraction of said bolt, a bolt retracting element rotatably mounted in said housing, flexible means to connect said element with said member whereby rotation of said element retracts said member and accordingly said bolt, and means on said retracting element operatively associated with said assembly to be locked against movement thereby when the assembly is moved to its locking position whereby said assembly is operable to lock both said bolt moving member and said bolt retracting element.

2. A lockset in accordance with claim 1, wherein in said locking hub assembly includes abutment means and the means for moving the assembly includes a rotatable member and cooperating formations on said abutment means and said rotatable member, whereby rotation of said rotatable member in one direction effects movement of said abutment means into locking position in relation to said bolt moving member and said bolt retracting element, movement of said rotatable member in the opposite direction effecting movement of said abutment means to unlocking position.

3. A lockset in accordance with claim 1, wherein in the locking hub assembly comprises a pair of links, and the means for moving the assembly includes a rotatable eccentric member, said links respectively having angularly displaced slots formed therein through which said eccentric member extends to support the links, and whereby rotation of said eccentric member in one direction moves said links along angularly displaced paths into their locking positions relative to said bolt moving member and to said bolt retracting element.

4. A latch bolt assembly for a lockset comprising, in combination, a generally cylindrical housing comprising a pair of stamped sheet metal

75

12

side members, said members having juxtaposed flat side walls at one end thereof forming a guideway for a bolt, a bolt slidably mounted between said flat side walls, a bolt operating element movably mounted in said housing near the other end thereof, and a flat elongated connection member disposed within said housing between said bolt and said operating element, said member being attached to said bolt and operatively connected to said element so as to retract said bolt when said element is moved, said side members including juxtaposed crimped portions intermediate their ends having opposed flat surfaces forming bearings and guideways for the opposite faces of said flat connection member.

5. A latch bolt assembly for a lockset comprising, in combination, a generally cylindrical housing comprising a pair of stamped sheet metal side members, said members having juxtaposed flat side walls at one end thereof forming guideways for a bolt, a bolt slidably mounted between said flat side walls, a bolt operating element movably mounted in said housing near the other end thereof, a flat elongated connection member disposed within said housing between said bolt and said operating element, said member being attached to said bolt and operatively connected to said element so as to retract said bolt when said element is moved, said side members including juxtaposed crimped portions intermediate their ends having opposed flat surfaces forming bearings and guideways for the opposite faces of said flat connection member, and a spring associated with said connection member for biasing it in one direction, said housing side members being crimped intermediate their ends to form a cylindrical chamber at least partially closed at one end and open at the other for the reception and support of said spring.

6. A latch bolt assembly for a lockset comprising, in combination, a generally cylindrical housing comprising a pair of stamped sheet metal side members, said members having juxtaposed flat side walls at one end thereof forming guideways for a bolt, a bolt slidably mounted between said flat side walls, a bolt operating element movably mounted in said housing near the other end thereof, and a flat elongated connection member disposed within said housing between said bolt and said operating element, said member being attached to said bolt and operatively connected to said element so as to retract said bolt when said element is moved, said side members including juxtaposed crimped portions intermediate their ends having opposed flat surfaces forming bearings and guideways for the opposite faces of said flat connection member, said housing side walls having opposed bearing portions formed therein to mount said bolt operating member.

7. A latch bolt assembly for a lockset comprising, in combination, a generally cylindrical housing comprising a pair of stamped sheet metal side members, said members having juxtaposed flat side walls at one end thereof forming guideways for a bolt, a bolt slidably mounted between said flat side walls, a bolt operating element movably mounted in said housing near the other end thereof, a flat elongated connection member disposed within said housing between said bolt and said operating element, said member being attached to said bolt and operatively connected to said element so as to retract said bolt when said element is moved, said side members including juxtaposed crimped portions intermediate their

ends having opposed flat surfaces forming bearings and guideways for the opposite faces of said flat connection member, said housing side walls having opposed bearing portions formed therein to mount said bolt operating member, and a latch device mounted in the other end of said housing adjacent that end of said elongated connection member which is remote from said bolt for locking said member and accordingly said bolt, said side members having bearing portions formed therein for mounting said latch device.

8. In a lockset, in combination, a housing, a bolt retractably mounted in said housing, a tailpiece having one end secured to said bolt, a bolt operating member including a drum rotatably mounted in said housing, a flexible element trained around said drum and connected thereto, and means connecting the ends of said flexible element to said tailpiece whereby rotation of said drum in either direction winds a portion of said element on said drum and thereby retracts said tailpiece and accordingly said bolt.

9. A lockset according to claim 8, wherein the ends of said flexible element slidably extend through portions of said tailpiece and have stop members secured to their ends to limit sliding movement of said flexible element ends relative to said tailpiece in one direction.

10. A lockset according to claim 8, wherein the ends of said flexible element slidably extend through portions of said tailpiece and have stop members secured to their ends to limit sliding movement of said flexible element ends relative to said tailpiece in one direction, and means disposed between said stop members and said tailpiece for supporting either or both ends of said flexible element when either or both of said ends remains stationary upon operation of said drum to retract said bolt.

11. A lockset according to claim 8, wherein the ends of said flexible element slidably extend through portions of said tailpiece and have stop members secured to their ends to limit sliding movement of said flexible element ends relative to said tailpiece in one direction, means disposed between said stop members and said tailpiece for supporting either or both ends of said flexible element when either or both of said ends remains stationary upon operation of said drum to retract said bolt, and an element on each end of said flexible element to limit the movement of said stop members toward those portions of said tailpiece which slidably receive said element ends.

12. In a lockset, in combination, a housing, a bolt retractably mounted in said housing, a tailpiece having one end secured to said bolt, a bolt operating member including a drum rotatably mounted in said housing, a flexible element trained around said drum and connected thereto, means connecting the ends of said flexible element to said tailpiece whereby rotation of said drum in either direction winds a portion of said element on said drum and thereby retracts said tailpiece and accordingly said bolt, said drum having a stop shoulder formed thereon, and means on said tailpiece engageable by said stop shoulder upon rotation of said drum and resulting retraction of said tailpiece for limiting rotation of said drum.

13. A locking assembly for a lockset wherein a bolt is mounted for movement between extended and retracted positions, said locking assembly including in combination, means including a rotatable member adapted on rotation in one direction or another to move said member into lock-

ing or unlocking position relative to said bolt; a rotatable drum detachably connected to said member, a second rotatable drum, a flexible element trained about and connected to said drums, and manually operable means for rotating said second drum, thereby to drive said first drum and accordingly said rotatable member to move said means between locking and unlocking positions.

14. A locking assembly for a lockset wherein a bolt is mounted for movement between extended and retracted positions, said locking assembly including, in combination, means including a rotatable member adapted on rotation in one direction or another to move said member into locking or

unlocking position relative to said bolt, a pair of rotatable drums which may be selectively detachably connected to said member, a third rotatable drum, a flexible element trained about and connected to said drums, and manually operable means for rotating said second drum whereby one of said pair of drums is driven accordingly to drive that one of said pair of drums which is connected to said member, the other of said pair of drums idling.

15. A locking assembly in accordance with claim 13 wherein said manually operable means which rotates said second drum includes a key operable device accessible from one side of a door on which the lockset is mounted, and a thumb knob accessible from the other side of the door, there being an interconnection between the key operable device and the thumb knob for permitting operation of the thumb knob independently of the key operable device.

16. A locking assembly in accordance with claim 13 wherein the flexible element comprises a stranded steel cable of great tensile strength but slight elasticity.

17. A locking assembly in accordance with claim 13 wherein said drums are rotatably mounted in a shallow casing adapted to be secured to one side of a door to which the lockset is attached.

18. A lockset in accordance with claim 8, wherein said flexible element comprises a stranded steel cable.

19. In a lockset, in combination, an elongated housing adapted to be received in a mortise or the like in a door, a bolt slidably mounted in one end of said housing and movable between extended and retracted positions, a locking hub assembly mounted in the other end of said housing and movable between locking and unlocking positions, an elongated bolt moving member disposed within said housing and secured at one end to said bolt, the other end of said member lying adjacent said assembly when said bolt is in extended position, means for moving said assembly to its locking position wherein it lies in the path of retracting movement of said member thereby to preclude retraction of said bolt, said locking hub assembly including an abutment member and the means for moving the assembly including a rotatable member, and coacting formations on said abutment member and on said rotatable member for moving said abutment member into locking position relative to said bolt moving member when said rotatable member is turned in one direction, and for moving said abutment member out of locking position when said rotatable member is turned in the other direction.

20. In a lockset, in combination, an elongated housing adapted to be received in a mortise or the like in a door, a bolt slidably mounted in one

end of said housing and movable between extended and retracted positions, a locking hub assembly mounted in the other end of said housing and movable between locking and unlocking positions, an elongated bolt moving member disposed within said housing and secured at one end to said bolt, the other end of said member lying adjacent said assembly when said bolt is in extended position, means for moving said assembly to its locking position wherein it lies in the path of retracting movement of said member, thereby to preclude retraction of said bolt, said locking hub assembly including a link and the means for moving the assembly including a rotatable eccentric member on which the link is mounted so that when the eccentric member is rotated in one direction said link is moved into locking position, said link being moved to unlocking position by said eccentric member upon rotation thereof in the opposite direction.

21. In a lockset, in combination, a housing adapted to be received in a mortise or the like in a door, a bolt slidably mounted in one end of said housing and movable between extended and retracted positions, a locking hub assembly mounted in the other end of said housing and movable between locking and unlocking positions, a bolt moving member disposed within said housing and secured at one end to said bolt, the other end of said member lying adjacent said assembly when said bolt is in its extended position, means for moving said assembly to its lock-

5
10

ing position wherein its lies in the path of retracting movement of said member, thereby to preclude retraction of said bolt, a rotatable element located at a position remote from said assembly, and means forming a driving connection between said element and said assembly moving means to actuate said assembly moving means when said element is rotated, said assembly moving means including a rotatable part, the axis of said part being spaced from but parallel to the axis of said rotatable element.

22. A lockset in accordance with claim 21, including a pair of selectively manually operable devices connected to said rotatable element for effecting rotation thereof, said devices being located on opposite sides of said lockset.

Certificate of Correction

Patent No. 2,541,723

February 13, 1951

DUNCAN SHAW ET AL.

It is hereby certified that error appears in the printed specification of the above numbered patent requiring correction as follows:

Column 13, line 74, for the word "adopted" read *adapted*;
and that the said Letters Patent should be read as corrected above, so that the same may conform to the record of the case in the Patent Office.

Signed and sealed this 3rd day of July, A. D. 1951.
